UNITED STATES PATENT OFFICE.

SALOMON HEIMANN, OF NEW YORK, N. Y.

GLOBE FOR ELECTRIC LAMPS.

SPECIFICATION forming part of Letters Patent No. 393,704, dated November 27, 1888.

Application filed April 19, 1888. Serial No. 271,185. (No model.)

To all whom it may concern:

Be it known that I, SALOMON HEIMANN, of the city, county, and State of New York, have invented certain new and useful Improvements 5 in Globes for Electric and other Lamps, of which the following is a specification.

This invention relates to an improved globe for electric and other lamps, by which the light of the lamp is diffused in a very effective manner; and the invention consists of a globe for electric and other lamps which is provided with an annular biconvex portion, which acts in the nature of an annular lens for distributing the light-rays of the lamp.

15 In the accompanying drawings, Figure 1 represents a vertical central section of a globe made according to my invention. Figs. 2 and 3 are vertical central sections of lamp-chimneys of different forms made on the same principle; and Figs. 4 and 5 are horizontal sections on line $x x$ and $y y$, Fig. 2.

Similar letters of reference indicate corresponding parts.

Referring to the drawings, A represents a 25 globe for electric, incandescent, or other lamps, the body of which is made of annular shape and

biconvex cross-section, which serves to diffuse the light of the lamp in a more effective manner than with plano-convex lenses, while the same can be manufactured with less difficulty. 30 This principle is also adapted to be used for chimneys of gas or petroleum lamps in which that portion of the chimney encircling the flame is made of annular shape and of biconvex or lens-shaped cross-section, as shown in Figs. 2 35 and 3.

I am aware that plano-convex globes are old and well known; also, that hollow biconvex lenses were used before, and I do not claim these features, broadly.

Having thus described my invention, I claim as new and desire to secure by Letters Patent—

A globe or chimney for electric and other lamps, provided with a solid annular biconvex body, substantially as set forth.

In testimony that I claim the foregoing as my invention I have signed my name in presence of two subscribing witnesses.

SALOMON HEIMANN.
